HAND LOOM

Milo O. Gallinger, Hartland, Mich., assignor to
J. Roberts Crouse, Cleveland Heights, OhioOriginal application May 13, 1938, Serial No.
207,690. Divided and this application April 12,
1941, Serial No. 388,290

2 Claims. (Cl. 139—33)

This invention relates to improvements in looms and particularly looms of the hand-operated type, the present application being a division of my earlier application Serial No. 207,690, filed May 13, 1938.

A major object of the invention is to provide a hand-operated loom of the type in which the warp is wound around the rectangular frame of the loom and in which the frame structure is adjustable in length and has an improved construction facilitating both assembly of the structure and operation of the loom in weaving.

Other objects of the invention more or less incidental or ancillary to the foregoing will appear as the description proceeds.

With the noted objects in view the invention consists in various features of construction, arrangements and combinations of parts which will be pointed out and explained with reference to a loom of preferred form shown in the accompanying drawing.

In the drawing,

Fig. 1 is a plan view of the main parts of a loom embodying my improvements.

Fig. 2 is a vertical section on the line 2—2 of Fig. 1.

Fig. 3 is a vertical section on the line 3—3 of Fig. 1.

Fig. 4 is a vertical section on the line 4—4 of Fig. 1.

Fig. 5 is a front elevation of the combined beater and comb of the loom, the top bar of the device being partially removed and a portion of the structure being broken away to disclose details of the construction.

Fig. 6 is a fragmentary perspective view showing one of the heddle bars and the looped heddle cord for raising certain of the warp threads to make the shed in the weaving operation.

The hand loom shown in the drawing is of the type having a rectangular frame around which the warp thread is continuously wound, the rotatable warp and cloth beams of the older forms of construction being replaced by rigidly fixed beams constituting the end bars of the rectangular frame.

Referring in detail to the construction shown in the drawing, the numeral 1 designates the frame structure of the loom in its entirety, said structure being preferably formed of wood. This frame structure comprises a rear cross bar 2 serving as the rear or warp beam of the loom, forwardly extending side bars 3, 3 rigidly attached to the rear beam 2 as by screws 4, 4, a front or cloth beam 5, and rearwardly extending

side bars 6, 6 rigidly connected to the beam 5 by screws 7, 7. The side bars 6, 6 are slidably engaged by the side bars 3, 3 and the two pairs of bars are formed, respectively, with mutually engaging tongues 6^a and grooves 3^a and said bars are disengageably clamped in adjusted position in relation to each other by a strut or spacing bar 8 and tension rod 9. The strut 8 extends across the frame 1 with its ends engaging the inner sides of bars 3, 3 and is slotted lengthwise (Fig. 2) to receive rod 9. Said rod extends through a slot 3^b in each bar 3 and through transverse holes in bars 6, 6. The threaded ends of rod 9 are fitted with wing nuts 9^a, 9^b which can readily be manipulated to loosen the tension rod and permit adjustment of the length of the rectangular frame formed by the beams 2, 5 and side bars 3, 6, endwise movement of bars 3, 3 relative to rod 9 being permitted by the elongated slots 3^b, 3^b.

As the frame 1, in the operation of the loom, is designed to rest upon a table or the like it is fitted with feet 10, 10 and 11, 11. The feet 10, 10 are secured by screws 10^a, 10^b to beam 2 and the feet 11, 11 by screws 11^a, 11^b to side bars 6 and beam 5.

To facilitate the equal lengthwise adjustment of the two sides of frame 1, I form, as with a suitable stamping or printing die, a measuring scale 3^c on each of the bars 3, said scales being arranged as shown in Fig. 1 so that their graduations come adjacent the rear ends of the frame bars 6, 6. In addition each side of frame 1 is fitted with a threaded rod 12 which is fixedly secured at its rear end to foot 10 and has its front part supported in a slotted bar 13 secured by screws 14, 14 to the under side of bar 6 (Figs. 2 and 4). A wing nut 15 is mounted on each rod 12 to bear against the rear end of bar 13 and by use of the wing nuts it is easy to adjust the two sides of the frame 1 accurately to the same length, whereupon by tightening one of the wing nuts 9^a the sides of frame 1 are tightly clamped in adjusted position.

To facilitate weaving operations, as later explained, the frame 1 is provided with a transverse scale bar 16 at its front end and with a similar bar 17 at its rear end. These bars are graduated in inches with zero in the center of the frame and read from zero upward both to the left and the right, as shown in Fig. 1.

The frame structure of the loom further comprises two heddle bar standards 18, 18, one of which is rigidly mounted on top of the rear end of each of the side bars 6, 6, the standards being secured to the side bars by screws 19, 19,

Each standard 18 comprises a main body part 18^a and a top cap member 18^b secured to the body 18^a by screws 20, 20. The part 18^a of each standard is in the form of a rectangular wood block which may readily be formed from boards of suitable width and thickness. The block 18^a of each standard is formed with four vertical transverse slots 18^c, 18^c to support heddle bars 21, 21 which are preferably in the form of straight bars of metal fitted at both ends with grips 22, 22 in the form of sections of rubber tubing which are pressed over the ends of the bars and frictionally held thereon. The grips 22 serve the additional function of holding the heddle bars against endwise displacement from the slots of the standards 18. The upper ends of the slots 18^c are closed by the caps 18^b as shown in Fig. 2.

Each of the standards 18 is formed with a deep slot 18^d disposed between and parallel to the lateral faces of the standards, such slots 18^d being provided to receive in each standard a heddle bar holder 23 which is formed with a series of upstanding fingers 24, 24 and which is pivotally supported at its lower rear corner on a pin 25 extending transversely through the standard 18. A block 26 of rubber or the like is cemented in the groove 18^d to support the lower front corner of the holder 23 and serves to cushion and quiet the action of the holder when it falls under the action of gravity, as will later be explained.

The holder 23 is preferably stamped from a metal sheet or plate to give the fingers 24, 24 the form shown in Fig. 3. Each of four of the said fingers is formed with a top edge or surface 24^a adapted to support one end of a heddle bar when the latter is in raised position and is also formed with a front edge or surface 24^b which is disposed as shown in Fig. 3 to be engaged by the top rear corner of the heddle bar when it is raised from its lower position to its upper position and by such engagement effect a backward swinging movement of the holder 23 on its pivot pin 25. When the holder 23 is thus swung backward by the lifting of any one or more of the heddle bars the finger surfaces 24^a are moved from beneath any heddle bars in raised position and the latter bars are permitted to drop into the slots between the fingers 24. The fifth or front finger of the support 23 extends forward from the standard 18 so that it can be engaged by the thumb or finger of the weaver to lift the holder 23 and release all heddle bars in the raised position and permit them to fall to their lower positions.

The front portion of the loom frame structure comprising beam 5, side bars 6, 6 and standards 18, 18 is strengthened by a cross rod 27 and a cross bar 28 which connect standards 18 as shown in Figs. 1 and 2. Bar 28 is secured by removable screws 29 and can readily be detached if desired when the warp thread is being wound upon the frame. The upper edge of bar 28 is slotted at 28^a to receive and support a card bearing the design or notations of the pattern to be woven.

In the loom illustrated each of the heddle bars 21 is fitted with a heddle cord 30 which is knotted at 30^a, 30^a to form a series of loops 30^b, 30^b which loosely surround the heddle bar and a series of depending loops 30^c, 30^c, each of which passes under a warp thread *w* and serves to lift the latter when the heddle bar is raised. See Figs. 2 and 6.

The numeral 31 indicates as an entirety a combined beater and comb which comprises a rectan-

5 gular frame structure 32 preferably formed of wood and a comb 33 mounted therein, the comb preferably being formed in one piece from compressed sheet fiber material. The top bar 32^a of the frame 32 is removably secured to the remainder of the frame by pins 34. When the device is used as a reed or beater the bar 32^a is attached to the frame, as shown in Figs. 1 and 2, but by removing said bar 32^a the ends of the comb teeth are exposed and the device is adapted to be used as a comb to facilitate the winding and even spacing of the warp thread upon the frame of the loom. To accomplish this latter operation the beater is clamped to the cloth beam 5 by means of thumb nuts or bolts 35 carried by the beam, the bottom bar of the frame 32 being formed with notches 32^b adapted to fit over the bolts 35 and suitably locate the beater. When the beater has thus been clamped in position its top bar 32^a is detached to expose the upper, free ends of the teeth of the comb so that the warp thread, when wound around the frame of the loom (as indicated in Fig. 2), can have its successive turns disposed in the successive slots of the comb and so be evenly spaced across the frame. After the winding of the warp thread has been completed, the bar 32^a is again attached to the beater frame and the beater is detached from the cross bar 5 and is thus rendered free to function as a beater.

30 The operation of the loom will readily be understood without extended explanation. When the loom is to be set up to weave a particular article the length of the rectangular frame of the loom is first adjusted, if need be, to provide for the desired length of the article, bearing in mind that its maximum length is the lengthwise distance around the loom frame. Adjustment is facilitated if the frame is first collapsed to a slightly shorter size than is desired and then extended to the desired size by manipulation of wing nuts 15, the scales 3^c making it easy to adjust the two sides of the frame to equal lengths. This final adjustment may advantageously be made after the warp has been wound upon the frame, as hereinafter indicated, so as to effect the desired tensioning of the warp. It will be observed that adjustment of the length of the loom frame does not change the distance between the front beam and the heddle bars since the heddle bar standards 18 are fixed in relation to said beam. Hence, with any adjustment the operator can easily reach and manipulate the heddle bars.

55 Next the heddle bars 21 are removed from the frame. This is accomplished by moving the bars endwise through the slots 18^c of the standards 18, such movement serving to engage the grips 22 at one side of the loom against the adjacent standard to force said grips off their respective bars. Cross bar 28 may also be removed from the frame if desired to facilitate winding the warp upon frame 1. Next, the beater is clamped to the front beam 5 and its bar 32^a is detached 60 so that the slots of the comb 33 can receive the warp thread. The warp thread is now wound continuously around the loom frame, starting at or near one side thereof and with the successive turns of the thread in the successive slots of the comb so that the warp is distributed evenly across the frame. The transverse point at which the winding of the warp thread is started will depend upon the width of the cloth to be woven. The graduated scales 16 and 17, as will readily be understood, facilitate the winding of the warp

thread so that the warp will be centered on the frame regardless of the width of the work. It is convenient to wind the warp on the frame with moderate tension and then establish the desired working tension by adjusting the frame to a greater length.

The heddle bars may now be replaced with their respective heddle cords mounted thereon in accordance with the pattern to be woven. Assuming, for example, that the cord of the first (front) heddle bar is to lift every fourth thread or turn of the warp, the cord is stretched out across the frame beneath the top flight of the warp and the heddle bar is inserted through its slot in one of the standards 18 and threaded through the successive loops 30^b of the cord so that it loops 30^c will engage every fourth thread of the warp. Then the leading end of the heddle bar is passed through its slot in the other standard 18 and its grip 22 replaced. The remaining heddle bars are assembled in a corresponding manner. Finally, the top bar 32^a of the beater is restored and the beater is detached from the front beam 5 and the loom is ready for weaving.

In the weaving operation the shed is formed by manual lifting of one or more of the heddle bars. The operator, by placing a finger beneath the end of each bar to be lifted can easily lift both ends of any one or more of the bars simultaneously. When one or more of the heddle bars are so lifted the holders 23 are moved automatically, as previously described, so as to release the bar or bars which had been lifted to form the last preceding shed. If it is desirable at any time to lower all of the heddle bars, the operator needs only to lift the front fingers 24 of the two holders 23 and this allows any elevated heddle bars to fall.

It will now be apparent that a loom such as has been described, because of its simple construction, can have its parts formed and assembled at low cost and, for the same reason, can easily and rapidly be manipulated in threading the loom and preparing it for a particular piece of weaving. Furthermore, its improved features of construction make the loom susceptible of easy operation at good speed to produce a wide variety of work of excellent quality.

In the present application I make no claim to the heddle harness comprising the heddle bars and devices for controlling their positions in the shed forming operation during weaving, as these parts of the apparatus are claimed in my earlier filed application previously referred to.

While the construction illustrated and described is such as I prefer, it is to be understood that my invention can be carried out with other forms of construction within the scope of the appended claims.

What I claim is:

1. In a loom, the combination of a frame structure having a cloth beam, side bars attached to and extending rearward from the end parts of the cloth beam, heddle bar standards rigidly mounted on said side bars, a warp beam, side bars attached to and extending forward from the end parts of the warp beam and having slidably adjustable engagement with the side bars of the cloth beam to permit variation of the length of the frame and of the cloth to be woven, clamping means for holding the mutually engaging bars of each of the two pairs of side bars of the frame in adjusted position comprising a transverse strut bar having its ends engaging the inner side bars of the two pairs thereof, a transverse tension rod carried by the side bars of the cloth beam in fixed relation to said beam and adjacent to the strut bar, and means associated with the ends of the tension rod for engaging the outer side bar of each pair of bars to apply tension to the rod and clamp the mutually engaging side bars of each side of the frame against the adjacent end of the strut bar; and manually operable shed-forming heddle bars mounted on said standards of the frame to cooperate with warp threads supported by the warp and cloth beams.

2. In a loom, the combination of a frame structure having a cloth beam, side bars attached to and extending rearward from the end parts of the cloth beam, heddle bar standards rigidly mounted on the said side bars, a warp beam, side bars attached to and extending forward from the end parts of the warp beam and having slidably adjustable engagement with the side bars of the cloth beam to permit variation of the length of the frame and of the cloth to be woven, clamping means for holding the mutually engaging bars of the frame in adjusted positions; means for facilitating the adjustment of the two sides of the frame to equal lengths comprising measuring scales disposed on the forward extending side bars adjacent to the side bars attached to the cloth beam, a pair of threaded rods respectively secured at their rear ends to the end parts of the warp beam and having their front parts telescopically engaging with the adjacent side bars of the cloth beam and nuts on the threaded rods to engage the last named side bars, whereby the two sides of the rectangular frame can be nicely adjusted with respect to the measuring scales by manipulation of the said nuts; and manually operable shed-forming heddle bars mounted on the said standards of the frame to cooperate with warp threads supported by the warp and cloth beams.

MILO O. GALLINGER.

CERTIFICATE OF CORRECTION.

Patent No. 2,274,326.

February 24, 1942.

MILO O. GALLINGER.

It is hereby certified that error appears in the above numbered patent requiring correction as follows: In the grant, lines 2 and 12, and in the heading to the printed specification, line 4, name of assignee, for "J. Roberts Crouse" read --J. Robert Crouse--, as shown by the record of assignments in this office; page 3, first column, line 17, for "it" read --its--; and that the said Letters Patent should be read with this correction therein that the same may conform to the record of the case in the Patent Office.

Signed and sealed this 21st day of April, A. D. 1942.

(Seal)

Henry Van Arsdale,
Acting Commissioner of Patents.
